COAL TESTING APPARATUS

Ralph H. Jones, Cincinnati, Ohio, assignor to
Carter Coal Company, Washington, D. C.

Application July 18, 1933, Serial No. 681,040

6 Claims. (Cl. 35—16)

This invention relates to the testing of coal and has for its primary object to provide a device in which certain of the properties of coal from different sources may be compared under conditions closely approximating those of the conventional furnace.

Another object of the invention resides in removably mounting such a device in a cabinet so that it may be easily transported from place to place and removed from time to time for demonstrating purposes.

In selling a material such as coal it will be readily apparent that it is highly desirable to have some means for demonstrating under actual working conditions the qualities of the particular coal as compared to other coal, as for instance a coal which the prospective customer has been previously using. An ocular demonstration of the comparative volatility of the coals, the amount of smoke given off, the condition and constituents of the materials remaining in the grates, etc., would of course be much more effective in convincing a customer than would a vast amount of printed matter, salesmanship, etc. It is to provide a simple and convenient means for giving such a demonstration that the apparatus about to be described was devised.

Other objects and advantages of the invention will be apparent from the following description when taken in connection with the accompanying drawings, in which,

Figure 1 is a perspective view of the apparatus installed in its cabinet, one of the drawers being shown partly open in dotted outline.

Figure 2 is a vertical sectional view of the apparatus apart from its cabinet, parts being broken away, and

Figure 3 is a fragmentary end view thereof.

Referring to the drawings in greater detail the numeral 1 indicates the body of a case or cabinet in which the testing device may be stored when not in use, or for the purpose of transportation. The cabinet is provided with a door or closure 2 mounted on vertically spaced hinges 3, and a lock 4 for securing the door in closed position. At the upper end of the case a handle 5 is provided.

Normally disposed within the cabinet 1 is the testing apparatus generally indicated by the numeral 6, and overhanging ledges or cleats 6' are formed on the side walls of the cabinet to engage the lower or base portion of the device and hold the same against movement within the cabinet when the latter is being moved from place to place.

The testing device includes a lower body por-

tion 7 formed of wood or similar material and here shown as provided with three compartments 8, 9 and 10. These compartments are open at their forward ends and receive slidably mounted drawers 11, 12 and 13. In the embodiment shown the two end drawers 11 and 13 are shown as containing samples of coal and hence are provided with sliding covers 14 to confine the fumes. The middle drawer 12 may be used for storing small tools, cotton waste or the like; or if desired may be used for storing a third sample of coal, in which event it would also be provided with a cover.

Brackets 15, preferably of metal, are secured to the four corners of the body 7 as by means of screws 16 and extend vertically upward therefrom. The upper ends of the brackets are turned as indicated by numeral 17 and form the support for a horizontally disposed plate 18. A pair of laterally spaced openings 19 are formed in the plate and receive what may be termed miniature furnaces. Each furnace comprises a cylindrical sleeve 20 provided with an annular rib 20' on its exterior surface to engage the upper surface of plate 18, and a grate 21. The grates, which are preferably formed of chromium wire of small mesh, are of substantially semi-spherical shape and are supported in the upper ends of sleeves 22. The sleeves are formed with a plurality of tongues 23 at their lower ends which form the means for securing the sleeves to annular plates 24 which are in turn secured in any suitable manner to the lower ends of the elements 20.

Chimneys 25 of glass or similar transparent material are adapted to engage over the sleeves 20 and are seated on the annular ribs 20'. These chimneys must of course be raised in order to supply fuel to the grates and for other purposes, and to facilitate this operation the chimneys are preferably tied together by spring clips 26. The clips may be clamped to the chimneys by screws 27, and are also secured to a rod 28. This rod is slidably mounted in a socket member 29 fixed to plate 18 intermediate the two furnaces, and is prevented from rotating by means of its pin 30 which engages in a slot 31 formed in the socket member. By grasping the handle 32 on the upper end of rod 28 it will be apparent that the chimneys 25 may be simultaneously raised and lowered and will always be maintained in vertical alignment with their respective furnaces.

On the upper surface of the member 7 metal guideways 33 are preferably provided. On these guideways are slidably mounted burners such as

alcohol burners 34 provided with wicks 35, and the flanges on the guideways serve to center the burners directly under the respective grates.

A chimney cleaner 36 (Figure 1) is preferably carried in the cabinet 1 and a hook 37 provides a convenient means for supporting the same when not in use.

In the operation of the testing device, the same is first withdrawn entirely from the cabinet and 10 the chimneys 25 then raised or removed. A few lumps of the two specimens of coal which have been previously loaded into the drawers 11 and 13 are removed and placed in the two grates, care being taken to insure that the coal is not 15 mixed while being conveyed from the drawers to the grates. In this connection, it is desirable that the names of the coal in the respective drawers be indicated on the drawers as represented by numeral 36. After the grates are charged 20 with coal the burners 34 are withdrawn and lighted, after which they are slid back into the guideways 33, care being taken to have them engage the rear flange and thereby insure their perfect centering under the grates.

In a very short time the coal in the grates or 25 miniature furnaces will become ignited and the two different grades will at once begin to show their different characteristics. For instance, the volatility of the two coals will immediately be apparent to observers skilled in the art. Likewise the amount of smoke or unconsumed carbon given off by the two coals will be indicated as it travels up the respective chimneys. Furthermore, after the actual demonstration is 30 completed an examination of the residue in the grates and the conditions of the chimneys will be a source of considerable interest to the observers in that it will give further indications of the qualities of the two coals.

From the foregoing description and the attached drawings it will be apparent to those 35 skilled in the art that I have devised an extremely simple and inexpensive apparatus in the form of miniature furnaces whereby different grades of coal may be compared under conditions substantially the same as would be encountered in normal operation of a furnace; that the device provides an ocular demonstration of two grades of coal in actual use and thereby affords a comparative estimate of their values; that it is ex-

tremely simple in operation, and that it may be manually transported from place to place and set up for operation at a moment's notice.

In accordance with the patent statutes I have described what I now believe to be the preferred 80 form of the invention, but inasmuch as various minor changes may be made in the details of construction without departing from the spirit of the invention it is intended that all changes 85 be included within the scope of the appended 85 claims.

What I claim is:

1. A device of the class described including a base, a pair of grates supported above the base, and adapted to receive samples of coals, and a 90 pair of burners disposed below the grates.

2. A device of the class described including a base, a plate spaced above the base and supported thereby, said plate provided with a pair of openings, grates disposed in said openings, and 95 a pair of burners removably mounted between the base and said grates.

3. A device of the class described including a base, a pair of grates supported above the base, transparent chimneys extending upwardly from 100 said grates, and a pair of burners disposed below the grates.

4. A device of the class described including a base, a pair of grates supported above the base, transparent chimneys extending upwardly from 105 said grates, a vertically movable rod mounted between the chimneys, and means for connecting the chimneys to the rod.

5. A device of the class described including a base, a plate spaced above the base and supported thereby, a pair of grates mounted in the plate, transparent chimneys extending upwardly from the grates, a vertically movable rod supported on the plate between the grates, and 110 clamps carried by the rod and adapted to secure the chimneys thereto.

6. A device of the class described including a base, a plate spaced above the base and supported thereby, a pair of grates mounted in the plate, chimneys extending upwardly from the 120 grates, a slotted socket member on the plate, a rod slidably mounted in the socket member, a pin on the rod and extending into said slot, and means for securing the chimneys to the rod.
